Patented Apr. 4, 1972

223,280

FINDING FOR A BROOCH OR THE LIKE

Leonard Page, Levittown, N.Y., assignor to Dynamic Learning Media, Inc., Farmingdale, N.Y.

Filed Apr. 13, 1970, Ser. No. 22,413

Term of patent 14 years

Int. Cl. D11—01

U.S. Cl. D45—19

FIG. 1

FIG. 2

FIG. 1 is a top plan view of a finding for a brooch or the like, showing my new design.

FIG. 2 is a side elevational view.

The stippled areas in FIG. 1 represent the color black.

I claim:

The ornamental design for a finding for a brooch or the like, substantially as shown and described.
